Frank W. Briesen

UNITED STATES PATENT OFFICE.

FREDERICK W. BRIESE, OF JAMAICA, NEW YORK.

GARBAGE-CAN.

1,226,634.

Specification of Letters Patent.

Patented May 22, 1917.

Application filed December 27, 1916. Serial No. 139,177.

To all whom it may concern:

Be it known that I, FREDERICK W. BRIESE, a citizen of the United States, and a resident of Jamaica, in the county of Queens 5 and State of New York, have invented certain new and useful Improvements in Garbage-Cans, of which the following is a specification.

This invention relates to a garbage can 10 of novel construction in which the escape of foul odors, while the can is being charged is prevented, while furthermore, the spilling of the garbage as the can is dumped is effectively avoided.

15 In the accompanying drawing:

Figure 1, is a longitudinal section on line 1—1 Fig. 2, of the garbage can embodying my invention;

Fig. 2, a plan with the cover removed and 20 the slide closed, and

Fig. 3, a cross section on line 3—3 Fig. 1.

The can body 1, is furnished at a suitable distance below its upper edge, with a grooved guide 2, for the reception of a slide 25 3, that is adapted to divide the can into a larger lower compartment 4 and a smaller upper compartment 5. The shape of slide 3, corresponds to the cross section of the can body 1 the slide being circular with the 30 cylindrical body illustrated.

The slide is provided with a semicircular flange 6 and a handle 7 and may be retracted from the can, through a semi-circular slit 8 formed within or opposite to 35 groove 2. In order to guide slide 3 during its movement there extends diametrically across can body 1 in proximity to slit 8, a rod 9 engaged by a pair of perforated lugs or members 10, that depend from the slide, 40 and of which the foremost lug likewise constitutes a stop which holds the slide to the can body in the open position of the former.

Within the upper compartment 5 there 45 extends from the inner wall of the can body, a chamber or pocket 11 which is adapted for the reception of a suitable disinfectant carrier 12. This carrier may be introduced through a larger opening 13 formed in the top of the pocket, while the disinfecting 50 vapors are discharged through smaller openings 14. The inner upright wall 15 of pocket 11, is made of convex form, so that

it will bulge into compartment 5 and constitute a scraper for the garbage as the slide is being retracted. In order to insure a 55 tight joint, for the latter, there is secured to the lower edge of wall 15 a packing strip 16, which extends likewise along the upper edge of slit 8 on the inner face of the can. A similar packing strip 17 is secured to said 60 inner face along the lower edge of the slit.

In use, slide 3 is closed, the cover 18 of the can is opened, and the garbage is thrown into the upper compartment 5, the disinfecting vapors escaping from pocket 11 65 while the cover remains open. The cover is then closed, the slide withdrawn to dump the garbage into the lower compartment 4 and the slide is again closed ready for the next charge.

70 When the contents of the can are to be transferred to the garbage collecting wagon, cover 18 is opened, but slide 3 remains closed until the can has been lifted into the wagon, so that in this way, any spilling 75 of the garbage is prevented.

I claim:

1. A garbage can comprising a can body having a slit, a slide engaging said slit and adapted to divide said body into a lower 80 compartment and an upper compartment, an apertured disinfecting chamber having a convex inner wall, an upper packing strip secured to the lower edge of said wall above said slit, and a lower packing strip secured 85 to the inner face of the can body below said slit.

2. A garbage can comprising a can body having a slit, a rod extending across the can body in proximity to said slit, a slide 90 engaging said slit and adapted to divide the can body into an upper compartment and a lower compartment, and a member on said slide that engages said rod.

3. A garbage can comprising a can body having a slit, a rod extending across the can body in proximity to said slit, a slide engaging said slit and adapted to divide the can body into an upper compartment and a lower compartment, an apertured disinfecting chamber located in the upper compartment, and a member on the slide that engages said rod.

FREDERICK W. BRIESE.
